(57) **CLAIM**

The ornamental design for a “circular connector,” as shown and described.

DESCRIPTION

FIG. 1 is a front and top perspective view of a “circular connector” showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear and top perspective view thereof.

The broken line in the figure drawing views is included to show unclaimed environment only and forms no part of the claimed design.
